US00D528072S

(12) **United States Design Patent** (10) Patent No.: **US D528,072 S**
Chen et al. (45) Date of Patent: ** Sep. 12, 2006

(54) **CHARGER FOR HANDHELD ELECTRONIC DEVICE**

(75) Inventors: **Kun-Hai Chen**, Taipei Hsien (TW); **Hao-Yu Tsao**, Taipei Hsien (TW); **Pin-Xian Su**, Taipei Hsien (TW); **Chao-Ning Chang**, Taipei Hsien (TW); **Yu-Liang Chiu**, Taipei Hsien (TW); **Hui-Shan Hsu**, Taipei Hsien (TW); **Wen-Jung Hsiao**, Taipei Hsien (TW)

(73) Assignee: **Acer Inc.** (TW)

(**) Term: **14 Years**

(21) Appl. No.: **29/196,776**

(22) Filed: **Jan. 6, 2004**

(30) **Foreign Application Priority Data**

Jul. 10, 2003 (TW) 92304302

(51) **LOC (8) Cl.** **13-02**

(52) **U.S. Cl.** **D13/108**

(58) **Field of Classification Search** D13/107-110, D13/118-119, 184; D14/251, 253, 432, 434; D16/219, 237, 242; 320/107-115

See application file for complete search history.

(57) **CLAIM**

The ornamental design for a charger for handheld electronic device, as substantially shown and described.

DESCRIPTION

FIG. 1 is a front perspective view of a charger for handheld electronic device showing our new design;

FIG. 2 is a front view of the charger for handheld electronic device;

FIG. 3 is a back view of the charger for handheld electronic device;

FIG. 4 is a right side view of the charger for handheld electronic device;

FIG. 5 is a left side view of the charger for handheld electronic device;

FIG. 6 is a top plan view of the charger for handheld electronic device; and,

FIG. 7 is a bottom plan view of the charger for handheld electronic device.
